UNITED STATES PATENT OFFICE

WILLIAM C. H. CUSHMAN, OF NORTH BENNINGTON, VERMONT, ASSIGNOR TO H. T. CUSHMAN MFG. CO., OF NORTH BENNINGTON, VERMONT

DESIGN FOR A TABLE OR SIMILAR ARTICLE

Application filed July 31, 1931. Serial No. 40,745. Term of patent 3½ years.

To all whom it may concern:

Be it known that I, WILLIAM C. H. CUSHMAN, a citizen of the United States, residing at North Bennington, county of Bennington and State of Vermont, have invented a new, original, and ornamental Design for a Table or Similar Article, of which the following is a specification, reference being had to the accompanying drawings, forming a part thereof.

I claim:

The ornamental design for a table or similar article as shown.

WILLIAM C. H. CUSHMAN.
